UNITED STATES PATENT OFFICE.

DWIGHT G. CLARK, OF PLAINVILLE, CONNECTICUT, ASSIGNOR TO CORRUGATED BAR COMPANY, OF ST. LOUIS, MISSOURI, A CORPORATION OF MISSOURI.

PROCESS OF MAKING EXPANDED METAL.

1,187,043.

Specification of Letters Patent. Patented June 13, 1916.

Original application filed May 20, 1908, Serial No. 433,958. Patent No. 1,080,418, dated December 2, 1913.

Divided and this application filed November 28, 1913. Serial No. 903,534.

To all whom it may concern:

Be it known that I, DWIGHT G. CLARK, a citizen of the United States of America, and residing at Plainville, in the county of Hartford and State of Connecticut, have invented new and useful Improvements in Processes of Making Expanded Metal, of which the following is a specification.

The main object of my invention is to produce metal mesh-work having special adaptability for use as concrete reinforcement. For this purpose, my invention contemplates the production of a fabric which consists of strips of metal spaced apart and integrally connected by metal mesh-work. The metal mesh-work is formed by slitting the metal stock with bands of characteristic slits alternating with unslotted strips, and spreading apart the parallel unslotted strips or portions. The unslotted strips or portions may have any cross-sectional shape desired by suitably forming these portions.

Other objects of my invention appear in connection with the following description of the several embodiments of the product illustrated in the accompanying drawings.

In the drawings:—Figure 1 is a plan view of a piece of metal stock slitted according to my invention, showing one arrangement of slitting preparatory to expansion. Fig. 2 shows the article produced from the stock shown in Fig. 1. Fig. 3 is an end view of the stock shown in Fig. 1. Fig. 4 is a cross section of the article shown in Fig. 2, taken on the line 4—4 in Fig. 2 looking in the direction of the arrows. Fig. 5 is a cross section similar to Fig. 4, showing the article in a modified form produced by bending the unslotted strips at right angles to the mesh-work. Fig. 6 is an end view similar to Fig. 3 showing the stock suitably formed for making an article having unslotted strips of square cross-section. Fig. 7 is a cross section of the article produced from the stock shown in Fig. 6. Fig. 8 is a plan view of a piece of metal stock showing an arrangement of slitting for producing an article having the meshes of successive mesh-work portions relatively staggered with respect to each other, instead of in line, as shown in Fig. 2. Fig. 9 is an end view of the stock shown in Fig. 8 in which the unslotted strips are round in cross section. Fig. 10 is a plan view of a piece of metal stock, show-

ing an arrangement of slitting for producing an article having mesh-work formed with two rows of meshes. Fig. 11 shows the article produced from the stock shown in Fig. 10.

Referring to Figs. 1 to 9 of the drawings, my improved expanded metal consists of a plurality of parallel strips 1 of metal spaced apart and connected by a series of integral frames 2 or mesh-work portions. Each frame consists of four strands 3, 4, 5, 6, forming a diamond-shaped mesh 7, and preferably turned on edge or inclined relative to the general plane of the article. Although I have shown only three unslotted strips, and two portions of mesh-work connecting said strips, the article may be of any width and contain any number of spaced strips connected as above described.

The mesh-work portions 2 between the unslotted strips may consist of double or triple rows of meshes, as shown in Figs. 10 and 11 according to the use to which the article is to be put; and the unslotted strips 1 likewise may be shaped as desired.

It is noted that there is no stretching of the metal during the operation of expanding or pulling out the mesh-work portions in making expanded metal in accordance with my invention, and hence the stock may be of harder metal, such as carbon steel, than could be utilized if the metal had to stretch. This advantage is attained by the system of slitting which characterizes my invention, in which, there are an odd number of rows of longitudinal slits and certain transverse slits. The longitudinal slits 8 of the odd numbered rows bordering the unslotted strips 1 on each side of the mesh-work portions 2 are connected at their middle points by cross slits 9, between the ends of the slits 10 in the even numbered rows, whereby the strands forming the meshes are severed between successive meshes lengthwise of the rows and upon expanding the metal the severed ends of the strands pull apart without stretching the strands.

Another advantage of this invention is the rapidity and ease with which the improved article can be manufactured. The fact that the longitudinal slits of one row are staggered relatively to the slits of the next adjacent row makes the problem of slitting comparatively simple, as it is only

necessary to cut the cross slits 9 so as to bisect and connect the two outer rows of longitudinal slits of each slitted portion of the stock. After slitting, the opposite sides 5 or margins lengthwise of the stock are spread apart to expand the metal to the desired extent.

Another advantage of this invention is the facility with which it may be adapted 10 to the production of different articles. For example, in case it is desired to make reinforcement for concrete slabs, the portions of the stock which ultimately form the unslotted strips 1, of the expanded metal may 15 be of enlarged cross section, as shown in Figs. 6, 7 and 9. For metal lathing purposes, and for concrete reinforcement in which tension bars are not required, some of the unslotted strips may be omitted and 20 thereby a larger proportion of the stock may be slotted and expanded, the expanded metal thus produced covering a greater area than that having unslotted strips between each row of meshes. In case it is desired 25 to stiffen the expanded metal lengthwise without enlarging the cross section of the stock, some or all of the unslotted strips may be made of sufficient width that they may be folded or bent lengthwise into ribbed 30 form in any well known manner.

Another advantage of this invention is that, by suitably expanding the metal, the strands 3, 4, 5, 6 may be caused to take an inclined or oblique position with respect 35 to the general plane of the expanded metal, whereby the expanded metal is stiffened crosswise and the mesh-work portions are adapted to become embedded and keyed in the concrete in a highly effective manner.

40 This application is a division of my application, Serial No. 433,958, filed May 20, 1908, which became Patent No. 1,080,418, December 2, 1913.

What I claim is:—

45 1. The process of making an expanded metal having longitudinal members transversely connected by independent disconnected meshed members, which consists in slitting a sheet of metal with series of longitudinal parallel slits made at intervals along said sheet, the outside lines of slits of said series of slits being coincident with the edges of the connected longitudinal members of said expanded metal; slitting said 50 sheet with other series of longitudinal parallel slits of substantially the same length as the first mentioned series of slits, parallel to, intermediate and between said first mentioned series of slits, the medial points in 55 said last mentioned series of slits being substantially equidistant from the medial

points of the adjacent slits of the first mentioned series, transversely cutting said sheets between the outside slits of the first mentioned series of slits between the edges 65 of said longitudinal members at the medial points of said slits of the first mentioned series; then stretching said slitted sheet laterally so as to form the meshed members thereof.

2. The process of forming expanded metal having longitudinal and meshed members, which consists in longitudinally slitting a metal sheet with series of lines of parallel alternating slits; transversely shearing said sheet between its longitudinal members at the medial points of one of said series of longitudinal slits so as to permit the forming of independent terminally disconnected and separated meshed members 75 transversely connecting the longitudinal members of said expanded metal; and expanding said slitted sheet.

3. The process of making expanded metal which consists in forming in a sheet, bands 85 of slits separated by unslotted bands, the slits of each slitted band being arranged in an odd number of rows, the slits of one row breaking joints with those of the adjacent rows of the same band, the slits of 90 the outermost or odd numbered rows of each band being connected by transverse slits which are clear of the slits in the even numbered rows.

4. The process of making expanded metal 95 which consists in slitting a sheet of metal in longitudinal bands, then opening out the slitted portion, the slits of each slitted band being arranged in an odd number of rows, the slits of one row breaking joints with 100 those of the adjacent rows of the same band, the slits of each odd numbered row being connected to the slits of the next odd numbered row by transverse slits passing between the ends of the slits of the intervening 105 even numbered row.

5. The process of making expanded metal which consists in forming bands of slits separated by unslotted bands, then opening out the slitted portion, the slits of each slitted band being arranged in an odd number of rows and the slits of one row breaking joints with those of the adjacent rows of the same band, and transverse slits which are located between the ends of slits in the 110 even numbered rows and which connect slits of the next adjacent odd numbered rows.

DWIGHT G. CLARK.
